Primary Examiner — Susan Bennett Hattan*Assistant Examiner* — Rebecca Tsehay(74) *Attorney, Agent, or Firm* — Grant IP, Inc.(57) **CLAIM**

The ornamental design for a pipette tip device in package, as shown and described.

DESCRIPTION

FIG. 1 is a front view of an assembly in which a pipette tip device is contained within a transparent, resealable plastic bag;

FIG. 2 is a back view of the assembly shown in FIG. 1; FIG. 3 is a side view of the assembly shown in FIG. 1 (the opposing side view is the same);

FIG. 4 is a top view of the assembly shown in FIG. 1;

FIG. 5 is a bottom view of the assembly shown in FIG. 1; FIG. 6 is a top perspective view of the assembly shown in FIG. 1; and,

FIG. 7 is a bottom perspective view of the assembly shown in FIG. 1.

Oblique lines on the pipette tip device in package surfaces indicate that those surfaces are transparent.
